ATTORNEY

UNITED STATES PATENT OFFICE.

FRANK C. SASAKI, OF POMONA, CALIFORNIA.

HANDCUFF HOLDER.

Application filed January 16, 1924. Serial No. 686,592.

To all whom it may concern:

Be it known that I, FRANK C. SASAKI, a citizen of Japan, residing at Pomona, in the county of Los Angeles and State of California, have invented new and useful Improvements in Handcuff Holders, of which the following is a specification.

This invention relates to improvements in holders for hand cuffs and has for an object the provision of a holder which may be carried upon the person and adjustably positioned upon a belt or the like so that the hand cuffs may be at all times accessible.

Another object of the invention is the provision of a hand cuff holder which will securely hold the hand cuffs against loss and in a manner to permit of quick and convenient removal when desired.

With the above and other objects in view, the invention further includes the following novel features and details of construction, to be hereinafter more fully described, illustrated in the accompanying drawings and pointed out in the appended claims.

25 In the drawings:—

Figure 1 is a perspective view showing the holder arranged upon a belt with a pair of hand cuffs shown by dotted lines in position upon the holder.

30 Figure 2 is a perspective view of the holder in open position and the hand cuffs removed.

Figure 3 is an enlarged longitudinal sectional view showing the holder in closed position.

35 Figure 4 is a transverse section.

Referring to the drawings in detail wherein like characters of reference denote corresponding parts, the reference character 10 indicates a belt which may be of any desired type, for example such a belt as is usually worn by an officer of the law for the purpose of supporting a revolver holster and for carrying ammunition. While the 40 holder is shown in connection with a belt of this character which is comparatively wide, it may be used with a belt of any character. The holder comprises a body 10 which is preferably formed of leather, the 45 opposite edges of the material being secured together as by stitching 11 so as to form a sleeve for receiving the belt 10. The inner portion of this sleeve, that is, the portion of the sleeve next to the body of the wearer is 50 preferably of the shorter length than the outer portion and the opposite ends of this

inner portion are preferably inclined as indicated at 12, so that the sleeve may be more comfortably worn.

The opposite or outer face of the sleeve 60 has secured thereon spaced disks 13 which are circular or substantially circular in shape so that the hand cuffs which are indicated at 14 may be positioned thereover, the width of the disks being sufficient for this 65 purpose.

Secured to the outer face of the sleeve is one end of a strap 15, the latter extending longitudinally of the sleeve across both of the disks and having its opposite end removably attached to the sleeve by a fastening device indicated at 16. This fastening device may be in the form of a snap fastener as shown. Similar fastening devices 17 are employed for securing the intermediate portions of the strap 15 to the disks 13, so that when the hand cuffs are placed over the disks and the strap secured in place by the fastening devices 16 and 17, the hand cuffs will be held securely in place, yet may be 80 readily removed when desired. The holder may be adjustably positioned upon the belt 10 for the convenience of the wearer.

The invention is susceptible of various changes in its form, proportions and minor 85 details of construction and the right is herein reserved to make such changes as properly fall within the scope of the appended claims.

Having described the invention what is 90 claimed is:—

1. A hand cuff holder comprising a body, means whereby the body may be secured in place, spaced cuff supporting disks secured to the holder, a strap having one end secured to the body and extending across the outer faces of the disks and means for detachably connecting the opposite end of the strap to the body and its intermediate portion to the disks. 100

2. The combination with a belt, of a hand cuff holder comprising a sleeve adapted to receive the belt, spaced cuff supporting disks secured to the sleeve, a strap having one end secured to the sleeve and extending across 105 the outer face of the disks and means for detachably connecting the opposite end of the strap to the sleeve and its intermediate portion to the disks.

In testimony whereof I affix my signature.

FRANK C. SASAKI.
